WINDING MACHINE STOP MECHANISM

Henry J. McDermott, Prospect Park, Pa., assignor to American Viscose Corporation, Wilmington, Del., a corporation of Delaware

Application July 8, 1943, Serial No. 493,809

4 Claims. (Cl. 242—36)

This invention relates to winding machines and more particularly to an improved device for arresting the operation of the machine whenever the yarn being wound becomes excessively tensioned and before such tension can reach the breaking stress of the material. Excessive tension in the yarn may result from various causes including the tendency of the yarn to adhere to the supply package or to catch upon irregularities of other windings of the supply package. The development of excessive tension may cause breakage of the yarn, irregularities in the wound package, and, where high tenacity yarns or cords are involved, damage to the machine, such as distortion of parts and excessive wear.

In accordance with the present invention, the yarn on its way to the winding spindle of the machine passes through a thread-storage loop which varies in size inversely with the tension in the yarn, and imparts movement to a member for initiating operation of the stop means when a predetermined tension is attained. Further objects and advantages will be apparent from the drawing and the description thereof.

In the drawing, illustrative of the invention,

Figure 1 is a front elevation of a conventional winding machine of the type shown in Wardwell Patent 801,941 (United States) and showing a preferred embodiment of the present invention applied thereto, and

Figure 2 is a side elevation of the machine of Figure 1.

While the invention will be described herein-after in relation to a particular type of conventional winding machine, it is to be understood that it is not limited to application thereto. In the description, the conventional parts of the winding machine will first be described and this will be followed by a description of the parts which constitute the present invention.

Referring to Figures 1 and 2 of the drawing, reference numeral 2 designates the fixed main frame of the machine. At the top of frame 2, a rotating spindle 3 is journaled in suitable bearings and is adapted to be driven by means of a belt pulley or other suitable mechanism (not shown). The spindle is adapted to receive a cone or cop tube 4 upon which the package 5 is to be wound.

A shaft 6 is journaled in the frame 2 and extends in a direction parallel to the winding spindle 3. This shaft 6 is connected to the spindle and is driven therefrom by suitable means, such as gears, a belt and pulleys, or sprockets and

chain, (not shown). The shaft 6 also carries a helical grooved cam 7 for rotation therewith.

A traverse frame 8 is pivotally mounted upon the shaft 6 upon which it is suitably balanced such as by the counterweight 9. This traverse frame 8 is provided with a backing plate 10 and a porcelain bail 11 may be rotatably supported on a wire 12 whose depending legs adjacent the ends of the bail are suitably fastened within recesses in the plate 10, by means of set screws 13. The traverse frame 8 is constructed to provide a horizontal groove through which a traverse bar 14 may reciprocate. A thread guide 15, whose upper end is adapted to press lightly against the package being wound is fastened to one end of the traverse bar 14 for reciprocation therewith. The other end of the traverse bar 14 is provided with a head 16 having a depending pin or roller 17 adapted to engage the groove in the helical cam 7. As the package builds up, it gradually swings the traverse frame 8 away from the spindle 3 and the traverse frame is prevented from swinging back toward the spindle by means of a lever 18 having one end fastened thereto at 19 and the other end engaging within a groove formed underneath a segment 20 which is pivotally fastened to the main frame 2 at 21.

The operation of the winding machine is controlled by a starting lever or handle 22, mounted on one end of a rotatable rod 23, supported in bearings at the top of the main frame 2.

The opposite end of the rod 23 carries means for operating a clutch or similar device (not shown) to control the operation of the spindle 3 and the other parts of the machine driven therefrom. A lever 24 is mounted adjacent the starting lever 22 on the rod 23 so that it rocks therewith. One end of lever 24 is normally biased in a counterclockwise direction by a spring 25 fastened to the frame 2 and is provided with a braking means 26 which is adapted to press against the spindle 3 and to stop the rotation thereof when the lever 22 is in the stop position in which position the clutch or other device for operating the spindle 3 is disengaged. The other end of the lever 24 is formed as a curved arm having a hook 27 at its end. When the starting lever 22 is in operating position, in which the clutch is engaged with the spindle 3 and the brake is lifted therefrom (as shown in Figure 1) the hook engages another hook 28 secured to or constituting part of the pivoted segment 20. The machine may be maintained in running position by setting these hooks 27 and 28 in opposition to the spring 25 which otherwise would tend to set the brake

and to swing the starting lever 22 into the stop position.

The pressure exerted by the guide 15 against the exterior winding of the package is controlled by a counterweighted arm 29 pivotally mounted on a bracket 30 fastened to the frame 2 of the machine. The link 31 is connected pivotally to arm 29 a short distance from its pivotal axis and is connected pivotally to the traverse frame 8 at 32. For adjustment, the end of link 31 may be inserted into any one of a series of sockets 33 provided.

A tension gate 34 in conventional construction is secured on bracket 30 and the tension exerted upon the yarn passing therethrough is controlled by a link 35 having one end attached to one of the grids of the tension gate 34 and the other end attached at 36 to a counterweighted arm 37 which is pivotally connected with the other arm 29. As the package grows in size, the arm 37 swings in a clockwise direction and thereby gradually reduces the tension exerted on the yarn by gate 34.

In operation of the machine, the yarn passes first through the tension gate 34 over the guide 38 of a sub-catcher, under a break or exhaustion detector 39, over the porcelain bail 11 and through the traverse guide 15 to the package. The break detector 39 comprises a device pivotally mounted at 40 upon segment 20. The device is composed of a bell crank lever 39a and two arms 41 and 42, one of which 41 extends toward a wheel 43 having numerous projections or ridges 44 thereon mounted upon the cam shaft 6 for rotation thereby. The other arm 42 is bent to form a horizontal extension 45 adapted to ride upon the yarn and along which the yarn may traverse to a certain extent. The extension 45 may be bent at the end to form a hook 46 to prevent the yarn from accidentally slipping out of engagement therewith. Arms 41 and 42 have the bent portions 41' and 42' which extend through holes in the bell crank lever 39a. Arm 42 is clamped in fixed relation to the bell crank lever 39a by the screw 42a and the slotted plate 39b. The arm 41 is preferably though not necessarily mounted for pivotal motion with respect to the device 39 as a whole and independently of arm 42. As shown, this may be accomplished by loosening the machine screw 41a which limits the counterclockwise swinging of arm 41 relative to the device 39. The first arm 41 is of such length and the entire detector device 39 is so balanced that upon breakage of the yarn, the device swings in a clockwise direction to bring arm 41 into the path of the projections 44 upon the rotating wheel 43 which in turn forces the segment 20 in a counterclockwise direction sufficiently to release the two hooks 27 and 28 and thereby permit the spring 25 to throw the starting lever 22 into the stop position to apply the brake and disengage the clutch. A projection 47 serves to limit clockwise motion of the detector 39.

The parts of the machine so far described are in the main part conventional and constitute no essential part of this invention except as will appear hereinafter. In accordance with this invention, the yarn or the like coming from a supply package proceeds through a guide 48 beneath the tension device 34 over a guide in the form of a rotatable pulley 49 which is swingably supported on a pivot 50. The pivotal member carrying the pulley 49 has a projecting arm 51 the upper end of which hooks over the plate 52 pivotally mounted at 53 and normally (that is during winding) is

retained in a notch 54 in plate 52. A projecting arm 55 extends upwardly from the plate 52 to a position beneath the arm 41 of the breakage and exhaustion detector 39. Plate 52 has an ear-like projection 56 having an arcuate contour starting adjacent the notch 54. An adjustable counterweight 57 is carried by an arm 58 on the pivotal support for the pulley 49.

The counterweight is adjusted to maintain the desired tension in the yarn loop. When during winding, this tension is exceeded, the loop about pulley 49 is reduced in size against the counterbalancing effect of the weight 57. Such motion causes counterclockwise swinging of projection 55 and swinging of arm 41 into wheel 43 and stopping of the machine. Since stopping is not always immediate, binding of the parts involved and consequent increase of tension in the yarn is prevented by the fact that the hooked end of arm 51 swings freely out of the notch 54 and rides over the ear 56 approximately at the instant that arm 41 engages the wheel 43. Thus, the reserve in the loop about the pulley 49 may be drawn upon without increasing the tension in the yarn.

In the present specification and claims, the term "package" is used in a general sense to indicate any form of wound mass and the term "yarn" is intended to designate any kind of strand material whether textile or otherwise.

While a preferred embodiment of the invention has been disclosed, it is to be understood that changes and variations may be made without departing from the spirit and the scope of the invention as defined by the appended claims.

I claim:

1. In a winding machine, a winding spindle, a traverse mechanism, means for swinging said spindle and traverse mechanism relative to each other about an axis substantially parallel to that of the spindle as the winding proceeds, means for stopping said machine automatically comprising an arm arranged to be swung into engagement with an operating member of said machine to initiate the operation of said stopping means, means comprising a movable guide responsive to the tension in the yarn for directing the yarn as it proceeds to the spindle through a yarn-storing loop and means associated with the guide for moving the arm into engagement with the operating member when the tension in the yarn increases to a predetermined extent.

2. In a winding machine, a winding spindle, a traverse mechanism, means for swinging said spindle and traverse mechanism relative to each other about an axis substantially parallel to that of the spindle as the winding proceeds, means for stopping said machine automatically comprising an arm arranged to be swung into engagement with an operating member of said machine to initiate the operation of said stopping means, means comprising a movable guide responsive to the tension in the yarn for directing the yarn as it proceeds to the spindle through a yarn-storing loop and means normally connected with the guide for moving the arm into engagement with the operating member when the tension in the yarn increases to a predetermined extent, the last-mentioned means being arranged to be disconnected from the guide approximately at the time of engagement of the arm with the operating member.

3. In a winding machine, a winding spindle, means for stopping the machine automatically comprising an arm arranged to be swung into

engagement with an operating element of the machine to initiate the operation of the stopping means, a pivotally mounted guide counterbalanced for directing the yarn as it proceeds to the spindle through a yarn-storing loop, a pivotally mounted member movable to engage the arm, and a releasable connection between the guide and the member arranged to be released upon motion of the member by the guide to effect initiation of the stopping means.

4. In a winding machine, a winding spindle, means for stopping the machine automatically comprising an arm arranged to be swung into

engagement with an operating element of the machine to initiate the operation of the stopping means, a pivotally mounted guide counterbalanced for directing the yarn as it proceeds to the spindle through a yarn-storing loop, a pivotally mounted member movable to engage the arm, a notch in the pivotally mounted member, a link extending from the guide normally engaged in the notch, the link being arranged to be released from the notch upon movement of the member by the guide to effect initiation of the stopping means.
